UNITED STATES PATENT OFFICE.

ANGUS F. HANNEY, OF CHICAGO, ILLINOIS, ASSIGNOR OF ONE-HALF TO ALEXANDER GAMMELL, OF CHICAGO, ILLINOIS.

LAUNDRY-TAG.

1,371,305.

Specification of Letters Patent. Patented Mar. 15, 1921.

Application filed March 12, 1918. Serial No. 221,899.

To all whom it may concern:

Be it known that I, ANGUS F. HANNEY, a citizen of the United States, and a resident of the city of Chicago, county of Cook, and 5 State of Illinois, have invented certain new and useful Improvements in Laundry-Tags, of which the following is a specification.

My invention relates to improvements in laundry tags and has for its object the production of an improved construction of this 10 character by means of which articles to be laundried may be readily marked for identification and said tags readily removed from said articles.

15 The invention consists in the combinations and arrangement of parts hereinafter described and claimed.

The invention will be best understood by reference to the accompanying drawings 20 forming a part of this specification, and in which,

Figure 1 is a perspective view of a construction embodying the invention shown in position for use,

25 Fig. 2, a transverse section of the same,

Fig. 3, an enlarged section of one of a plurality of laundry tags employed in the construction,

Fig. 4, an enlarged section taken on line 30 4-4 of Fig. 3, and

Fig. 5, an enlarged section taken on line 5-5 of Fig. 3.

The preferred form of construction as 35 illustrated in the drawing comprises a marking member 6 in the form of a hollow disk preferably made of two sheet metal stampings suitably secured together and provided in its lower edge with a notch 6' adapted to receive the edge of an article 7 to be laundried, as indicated. The member 6 is also 40 provided with a substantially inverted T-shaped opening 8 extending therethrough and with a slide 9 operating therein. The slide 9 is substantially in the form of a cross, having one arm 10 slidably mounted 45 between lips or flanges 11 and 12 struck from the sides of member 6, said arm being provided also with a depression 13 adapted to receive a bead 14 in the side of said member as indicated. The slide 9 is provided 50 with a plunger arm 15 sliding through a suitable slot in the edge of the member 6 and by means of which said slide may be moved in said member by forcing the arm 15 inwardly, the bead 14 engaging the depression

13 at the inner end of such movement to releasably lock the parts in such relation. The slide 9 also carries an upwardly extending arm 16 traversing one of the limbs of the opening 8 and with a depending arm 60 17 carrying the pin 18 traversing the notch 6'. The arrangement is such that the marking member 6 may be readily secured to the edges of various articles to be laundried by simply inserting said edges in the notches 65 6' and pressing on the plungers 15 to cause the pins 18 to penetrate the edges of said articles.

Coöperating with the marking members 6 is a supporting bar 19 removably mounted in 70 a suitable support 20, as indicated. The bar 19 is provided at its free end with a beveled nose 21 to facilitate the passage of the openings 8 in the marking members over said bar. Cam lugs 22 having their outer 75 edges beveled or slotted to constitute cam surfaces are arranged on opposite sides of bar 19 at a considerable distance from the outer free end thereof.

In use the marking members 6 are provided with suitable numbers, letters, or the like, for identifying the laundried pieces of different customers, and are secured to the edges of the articles to be laundried. After 80 the articles have been laundried, the same 85 are suspended on a bar 19 by passing the marking members 6 over said bar until all articles from any one customer have been thus suspended thereon, then the marking members 6 are forced inwardly on said bar 90 past the cam lugs 22, one or the other of said cam lugs striking the arms 16 of said marking members and releasing the pin 18 from the articles permitting the same to fall 95 into a receptacle or onto a surface provided therefor. This arrangement permits of the ready assembling of the articles of any one customer and of the practically simultaneous removal of all of the identification tags 100 therefrom. After the tags have thus been removed from the laundried articles, they in turn are removed from the bar 19 by removing said bar from its support 20 and sliding the laundry tags from the supported end of bar 19 whereupon the tags will be 105 assembled to correspond with the customers' articles in connection with which they have been used. This arrangement constitutes a simple and effective one for the purpose 110 and one which greatly facilitates the re-

moval of the laundry tags and also tends greatly to prevent their loss.

While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

Having described my invention, what I claim as new and desire to secure by Letters Patent is:—

1. In combination, a plurality of identical laundry marking members, each made comparatively small and flat; means on each of said marking members for detachably securing the same to an article to be laundried; a support adapted to receive a plurality of said marking members, said members being readily removable from and replaceable on said support; and means on said support for automatically releasing said members from the articles upon movement of said members along said support, substantially as described.

2. In combination, a plurality of identical laundry marking members made comparatively small and flat; means on each of said members for detachably securing the same to an article to be laundried; a readily detachable support for a plurality of said marking members, said members being readily removable from and replaceable on said support; and means located at one point of said support for automatically releasing all of said members from the articles upon movement of said members along said support, substantially as described.

3. A tag comprising a marking member; a shiftable pin on said member adapted to penetrate an article; a support for a plurality of said members; and means on said support for shifting said pin to release the articles, substantially as described.

4. A tag comprising a marking member; a shiftable pin on said member adapted to penetrate an article; a support for a plurality of said members; and means on said support for shifting said pin to release the articles when said members are moved from one position to another thereon, substantially as described.

5. A tag comprising a hollow marking member, there being a notch in one edge of said member and a substantially T-shaped opening extending through said member; a slot in said member, said slot carrying a pin traversing said notch and arm traversing said opening and a plunger protruding

from said member; a supporting bar for a plurality of said members; and cam members on opposite sides of said support positioned a considerable distance from the end thereof and arranged to operate said slide to release articles held by said pin, substantially as described.

6. In combination, a laundry marking member made comparatively small and flat and adapted to be secured to an article to be laundried whereby the same may be readily passed through laundrying machinery; means on said marking member for detachably securing the same to an article to be laundried; a support for a plurality of said marking members; and means on said support for releasing said members from the articles, substantially as described.

7. In combination, a laundry marking member made comparatively small and flat and adapted to be secured to an article to be laundried whereby the same may be readily passed through laundrying machinery, said marking member being perforated; means on said marking member for detachably securing the same to an article to be laundried; a support for a plurality of said marking members, the perforations in said marking members being adapted to slide over said support; and means on said support for releasing said members from the articles, substantially as described.

8. In combination, a plurality of identical laundry marking members, each made comparatively small and flat; means on each of said marking members for detachably securing the same to an article to be laundried; a support adapted to receive a plurality of said marking members; and means on said support for automatically releasing all of said members from the articles upon movement of said members on said support, substantially as described.

9. In combination, a plurality of identical laundry marking members made comparatively small and flat; means on each of said members for detachably securing the same to an article to be laundried; a support for a plurality of said marking members; and means located at one point of said support for automatically releasing all of said members from the articles upon movement of said members on said support, substantially as described.

In testimony whereof I have signed my name to this specification in the presence of two subscribing witnesses.

ANGUS F. HANNEY.
